CLAIM

The ornamental design for a cosmetic brush, as shown and described.

DESCRIPTION

[FIG. 1 is a top perspective view of a cosmetic brush showing my new design.]

[FIG. 2 is a top view of a cosmetic brush showing my new design; and.]

[FIG. 4 is a top view of a cosmetic brush showing a first embodiment my new design;]

[FIG. 5 is a side view thereof; and,

The ornamental design which is claimed is shown in solid lines in the drawings. The broken lines in the drawings are for illustrative purposes only and form no part of the claimed design.

1 Claim, 4 Drawing Sheets

Matter enclosed in heavy brackets [ ] appears in the original patent but forms no part of this reissue; matter printed in italics indicates the additions made by reissue.

Related U.S. Application Data

continuation of application No. 12/425,182, filed on Apr. 16, 2009, now abandoned.
